UNITED STATES PATENT OFFICE.

FREDERICK T. GREAVES, OF CHICAGO, ILLINOIS.

ROTARY DRYING APPARATUS.

Application filed June 8, 1921. Serial No. 475,959.

To all whom it may concern:

Be it known that I, FREDERICK T. GREAVES, a citizen of the United States, and a resident of Chicago, county of Cook, State of Illinois, have invented a certain new and useful Improvement in Rotary Drying Apparatus, of which the following is a specification.

This invention relates to drying apparatus of that kind in which the materials to be dried are introduced into a cylindric rotary structure through which heated air or gases or products of combustion are allowed to pass, usually through a flue extending longitudinally of the structure, so that the materials are tumbled about in the cylindric structure and dried in the desired manner before being discharged therefrom, the process being practically continuous.

Generally stated, the object of the invention is to provide a novel and improved construction of drying apparatus of the foregoing general character, having provisions for more satisfactorily supplying the cylindric rotary structure with the heated gases or products of combustion necessary for the drying of the materials, while the latter are tumbling about and gradually travelling through the structure, preferably from one end thereof to the other, thereby to insure the desired drying of the materials in an efficient manner.

Another object is to provide an improved construction and arrangement whereby the heat radiating surface of the heat flue is increased, for any given length of flue, without increasing the diameter thereof, and whereby the flue is materially stiffened or strengthened throughout its length, being formed with longitudinal fins or webs alternating with channels on the outer surface of the flue.

It is also an object to provide certain details and features of construction and combinations tending to increase the general efficiency and the desirability of a rotary drying apparatus of this particular character.

To the foregoing and other useful ends the invention consists in matters hereinafter set forth and claimed and shown in the accompanying drawings in which—

Figure 1 is a longitudinal section of a rotary drying apparatus embodying the principles of the invention.

Figure 2 is an enlarged transverse section

of the rotary cylinder and its flue on line 2—2 in Figure 1.

Figure 3 is an enlarged section on line 3—3 in Figure 1.

Figure 4 is an enlarged section on line 4—4 in Figure 1.

As thus illustrated, the invention comprises an outer horizontally disposed drum of any suitable character, such as the cylinder 1, provided with ring like tracks 2 that travel on rollers 3 suitably supported by bearings 4 mounted on the base 5 of the machine. A cog ring 6 encircles the cylinder and is engaged by a pinion 7 which is rotated by power communicated thereto from any suitable source and in any suitable manner. At one end the cylinder is tapered at 8 and has a rotary connection 9 with the intake 10 of the suction blower 11, which latter is mounted upon the roof of the furnace 12, this fan or blower being of any suitable or desired form or construction. A hopper 13 having a spout 14 extending through the tapered portion 15 of the blower intake provides means for feeding the materials into the dryer. As shown, the interior of the dryer cylinder 1 is provided with longitudinal ribs or fins 16 which carry the materials upward and then drop them. At its discharge end the cylinder 1 is provided with an outlet 17 and with radial wings or fins 18 that carry the materials upward a distance. A deflector 19 is arranged in position to deflect the materials carried upward by the radial wings or fins 18 into the discharge spout or outlet 17. Thus while the materials are continuously feeding through the spout 14 into one end of the dryer, the heated and dried materials are discharging from the outlet 17 at the other end thereof.

To supply the heat necessary for drying the materials, a flue 20 is provided and arranged to extend centrally and longitudinally of the interior of the cylinder 1, being suitably secured to the latter by brackets or arms 21, or in any suitable manner. The end of the flue adjacent to the spout 14 is closed by an end wall 22, but the sides of this end portion of the flue are provided with lateral intakes 23 which are tapered as shown toward the center of the flue, and which open on the sides of the cylinder 1, and which are thus constantly in communication with the chamber 24 of the furnace, so that the hot gases and products of com-

bustion which pass into this chamber from the combustion chamber of the furnace are admitted to the interior of the flue 20, during the operation of the dryer. The tapered intakes 23 act as funnels and keep the flue in communication with the furnace, much more effectively during the rotation of the flue, than would be the case if these intakes 23 were made straight. Hence a large volume of heat and products of combustion is taken into the fire, for any given size of drier. As the flue is open at its end 25, it follows that the strong draft or suction caused by the fan or blower 11 draws the gases and products of combustion through the flue and into the interior of the cylinder 1, in one direction, and then back in the opposite direction between the outer surface of the flue and the inner surface of the cylinder, whereby the materials gradually travel lengthwise of the dryer in one direction while the strong current of heated air and hot gases or products of combustion are caused to travel through and over the materials in the opposite direction. In other words, as shown in Figure 1, the materials being dried gradually progress or slowly travel toward the right, while the heated gases travel toward the left in the cylinder 1 of the dryer.

As a matter of further and special improvement, the tubular flue 20 is preferably constructed as shown more clearly in Figures 2 and 3, being composed of a plurality of trough-like sections 26 having their edges secured together at 27, thus providing the flue with external longitudinal fins or webs having channels between them. The diameter of the flue thus constructed is, of course, the diameter of the circle which intersects the outer edges of said fins or webs, and with this construction it will be seen that the heat radiating surface of the flue is much greater than would be the case if the walls of the flue were cylindrical and formed on the line of said circle. Thus the heat radiating surface of the flue is increased, without increasing its diameter, in the sense that its radiating surface is much greater than would be the case if the flue were simply a perfect cylinder equal in diameter to the diameter of the circle which intersects the extreme outer edges of the fins or webs formed at 27 by the edges of the different sections. Also, it will be seen that with this construction the radiating surface is greater than would be the case if the flue were cylindrical on the line of a circle intersecting the bottom of each section 26, and had radial wings or fins thereon to radiate the heat. The channeled or fluted formation of the heat flue 20, in the manner shown and described, tends also to stiffen the flue, as the fins or webs which extend parallel on the outer surface thereof serve

to materially stiffen the tubular structure thus provided, permitting the use of thinner sheet metal. In the construction of the flue in this way, any suitable or desired method can be employed, but as a matter of still further and special improvement the sections 26 are preferably formed by first rolling the sheet metal into cylinders, and by then dividing these cylinders longitudinally to form the trough-like sections. The sections thus produced are then turned wrong-side out, thereby to bring the channels into position to face outwardly, and the edge portions of the sections are then riveted or welded or otherwise secured together, whereby two-ply sheet metal fins or webs are formed which not only readily radiate the heat from the interior of the flue, but which also stiffen the latter and render the structure strong and rigid. The short flues or intake passages 23 may, of course, be formed in any suitable or desired manner from sheet metal, and serve also to rigidly connect the intake end of the flue 1 with the intake end of the outer rotary cylinder 1, and thus the entire cylindrical structure rotates about a horizontally disposed axis to tumble the materials about therein. The heated air or gases or products of combustion are admitted through the sides of the cylindrical rotary structure, but are discharged axially from the end of the cylinder, through the tapered portions 8 and 15, and through the blower intake 10 which forms a reduced axial end-portion, for the cylinder. The materials and the heat are introduced into the structure at the same end of the rotary cylinder, and the heat loaded with the moisture extracted from the materials is discharged from this same end, while the thoroughly dried materials are at the same time being discharged from the other end of the dryer. Also, it will be seen that the channels formed between the fins or webs 27 of the flue enable the latter, as it rotates, to carry the materials upward and over to the other side, as they fall from the carrying webs 16 previously mentioned whereby the materials may rest for a moment or two upon the flue, instead of instantly sliding off as would be the case if the flue had cylindrical side walls. In effect the flue formed as shown and described is provided with hollow fins or webs, instead of having solid metal fins or webs or ribs, and thus the internal capacity or area of the flue is greater than would be the case if it were cylindrical on the line of a circle intersecting the bottom of each trough-shaped section 26, each hollow web or fin having a certain amount of space therein which contributes to the total capacity, or cross-sectional area of the flue as a whole. With this construction, moreover, practi-

cally every inch of outer surface of the flue is formed by a comparatively thin layer of sheet metal which is all that is between the heated gases inside and the materials outside. Air enters the drum through the outlet 17 for the materials, and this air is heated and passes between the outer surface of the flue and the inner surface of the drum until it finally reaches the suction intake 10 of the fan or blower previously described. The heat in the flue vaporizes the moisture in the materials, and this moisture is carried along by the air and the hot gases, and before the gases and products of combustion escape from the open end 25 of the flue the heat thereof, to a large extent, passes through the thin walls of the trough-like sections 26 of the flue and is absorbed by the materials and air outside the flue. Practically, therefore, as stated, it is true that wherever the materials make contact with the outer surface of the flue they do so on a thin sheet metal wall the inner surface of which is in direct contact with the gases and smoke and products of combustion taken from the furnace or other means for supplying the heat. This would not be true, of course, if the longitudinal ribs or webs or fins provided on the flue 30 were solid, or not hollow, because in such case the materials could make contact with one surface of any fin or rib or wing and the opposite surface of this wing or fin would be a part of the outer surface of the flue, instead of a part of the inner surface thereof. Thus, as stated, the internal capacity or area of the flue is greater with the construction shown and described, and the direct radiating surface of the flue is greater than would be the case if the flue were cylindrical on the line of a circle intersecting the base or center portions or bottom of each trough-like section 26, with merely straight radial wings or fins of sheet metal on the outer surface thereof, assuming that these straight wings or fins were of such size that their outer edges terminated on the line of the circle (previously mentioned) intersecting the outer edges 45 of the flue shown and described; for with the latter construction as stated, the interior or space within the flue is practically extended outward into the two wings or fins themselves, thus providing hollow and internally heated wings or fins, instead of solid ribs or wings which would be dependent upon their points of attachment to the cylindrical flue for the transmission of heat to their outer edges.

It will be seen that passages 23 are tapered inwardly, so that they are funnel shaped, with the wide mouth of each funnel presented in position to receive the heated products of combustion from the furnace. The drum rotates at a greater speed than the flue, of course, inasmuch as the drum is of larger diameter than the flue, notwithstanding that they rotate in unison about a common axis, and hence the outer end of each passage 23 is advantageously 70 larger than its inner end, in the manner shown and described. Furthermore, it will be seen that the flue formed by the sections 26 is approximately cylindrical in form, being in one sense a fluted cylinder, for there are more than four sections and the width of each channel thus provided on the outer surface of the flue is approximately equal to one-half of the internal diameter of the flue, or at least less than said diameter. 75 Moreover, it will be seen that the flue is so supported in the drum that the materials can fall from the descending side of the flue to approximately the bottom of the drum as the materials will fall freely between the gaps provided between the wings or veins 16 and the outer edges of the flue; and, in addition, the structure thus provided affords free circulation of the heated air and products of combustion around or circumferentially of the flue during the operation of the drying apparatus; and, it will be seen that this free circulation of the gaseous elements circumferentially of the flue takes place before they pass between the inwardly tapered or funnel shaped passages 23, whereby very free circulation of both gases and the materials are ensured within the drum and around the outer surface of the heat flue. 80

It will be seen that the materials slide down the shoot or spout 14 and enter the drum without having to pass by the intake of the fan before entering the drum. Thus there is less danger of the materials being sucked into the fan, and better results are ensured. Furthermore, the tapered formation of the intake openings 23, as shown in Figure 2, tends to increase the period of time during which the intake of the flue 1 is in communication with the furnace or other source of heat. The circumference of the drum 1, of course, travels faster than the structure of the flue, when the entire structure is rotated, and it follows that by outwardly flaring the intake openings 23 it is easier for the heat and products of combustion to enter from the furnace, than would be the case if these openings 23 were made straight or with parallel sides, instead of with sides which are radial as shown in Figure 2 of the drawings. The inner flue is so formed that it has both external and internal channels, the external channels being more or less U-shaped in cross section, while the internal channels are substantially V-shaped in cross section. The walls 26 of the flue, however, constitute the entire flue structure and thus the walls which are necessary to enclose the interior of the flue 85

constitute everything that the flue involves in the way of structure. The heating materials have free and unrestrained circulation circumferentially around the flue in the manner shown and described.

What I claim as my invention is—

1. A drying apparatus comprising a rotary drum for receiving and tumbling about therein the materials to be dried, a flue extending longitudinally in said drum, suction means at one end of the drum to draw the air therefrom, feeding means at the same end to introduce the materials into the drum, said flue being externally and internally 10 channeled longitudinally thereof, means whereby said flue has a lateral intake on the side of said drum near said end thereof, and instrumentalities for supplying heat to said intake, said flue having an outlet to discharge the heat into the drum, whereby the heat is drawn through the flue in one direction and then through the drum and past said intake in the opposite direction by the suction means, and means to support the 15 flue in the drum without interfering with the free circulation of the heat circumferentially around the channeled outer surface of said flue, before passing said intake.

2. A structure as specified in claim 1, said 20 intake being formed by a plurality of inwardly tapered short passages extending outwardly from the sides of the flue and opening on the sides of the drum to communicate with said instrumentalities, each 25 passage having radial walls extending outward from the edges of the external channels of said flue.

3. A structure as specified in claim 1, said 30 drum being provided with an outlet for the materials and an inlet for air at the other end thereof, whereby air may enter and circulate freely circumferentially around said flue.

4. A structure as specified in claim 1, 35 said instrumentalities comprising a furnace having a chamber to receive the hot gases and products of combustion and wherein rotates the portion of the drum having said intake, whereby the furnace supplies heated 40 gases which are free to circulate circumferentially around said flue.

5. A structure as specified in claim 1, the 45 suction means comprising a blower having its intake connected axially to the end of said drum, whereby the blower 50 draws out the hot gases which have been free to circulate circumferentially around said flue.

6. In a drying apparatus, the combination 60 of a plurality of trough shaped sections having their edges united to form an approximately cylindrical flue having longitudinal 65 channels on the outer surface thereof, means whereby heated gases are caused to pass through said flue, and a rotary drum en-

closing said flue and adapted to receive the materials to be dried, with space between the drum and the flue to permit free circulation of the heat circumferentially around the channeled outer surface of said flue.

7. A structure as specified in claim 6, 70 said flue being suitably secured to the drum to rotate therewith, and to afford free circulation of the heat circumferentially around the outside of the flue.

8. A structure as specified in claim 6, said 75 flue having more than four of said sections and the width of each channel being less than the internal diameter of said drum, being supported to rotate with said drum.

9. In a drying apparatus, a rotary drum having one or more funnel-shaped or inwardly tapered side openings forming a lateral intake for heated gases to dry the materials, the intake openings being thus tapered to increase the area of communication with the source of heat at the outer end of each opening, and means to introduce the materials to be dried in said drum.

10. In a drying apparatus, the combination 90 of a furnace having a chamber to receive the heat and products of combustion, and a cylindric structure arranged to rotate in said chamber and having one or more funnel-shaped or inwardly tapered lateral 95 intake openings to receive the heated gases necessary for drying the materials in said dryer, the intake openings being thus tapered to increase the area of communication with the source of heat at the outer end of each opening.

11. In drying apparatus having a rotary drum, a tubular heat flue therefor, enclosed in said drum, comprising sheet metal sections secured together at their edges with their concave surfaces facing outward to provide external channels extending longitudinally of the flue and alternating with parallel fins or webs where said edges are secured together, there being more than 105 four of said sections and the width of each channel being less than the internal diameter of said drum.

12. In a rotary dryer, the combination of 110 a rotary drum in which the materials to be dried are received and tumbled about, a flue for heated gases extending centrally and longitudinally through the interior of said drum, lateral heat intake means extending through said drum to said flue, and means to draw the hot gases out axially from the end of said drum, said flue being rigidly connected to said drum, so that the two rotate in unison, without interfering with the free circulation of the hot gases circumferentially of said flue, within the drum, said flue having means on its outer surface adapted to catch and retain quantities of the materials dropped or thrown thereon by the rotation of the drum, and said means being 115 120 125 130

presented to the free circulation of the hot gases around the flue.

13. In drying apparatus, a cylindrical flue for heated gases in the form of a tubular structure having longitudinal hollow wings or fins forming external channels between them, so that the interior of the flue extends a distance into each wing or fin, the wings being hollow to a point near the outer edges thereof, and the width of each channel being approximately equal to one-half of the internal diameter of the flue.

14. In drying apparatus, a flue for heated gases therefor in the form of a tubular structure having longitudinal wings or fins forming channels between them, each wing or fin being hollow to permit the interior of the flue to extend to a point near the outer edge thereof, and means to support the flue in such a manner that the hot gases and materials have free circulation outside said flue circumferentially thereof.

15. In a rotary dryer, the combination of a rotary drum, and a flue for heated gases

therein, said flue having an interior chamber, 25 and having enclosing walls for said chamber, which enclosing walls are flush where they meet at their outer edges and constitute the entire structure of the flue.

16. In a rotary dryer, the combination of 30 a rotary drum, and a flue for heated gases therein, said flue having external and internal longitudinal channels, there being more than four relatively wide channels outside, and more than four relatively narrow 35 channels inside the flue.

17. In a rotary dryer, the combination of a rotary drum, a flue for heated gases therein, a fan having an intake to draw the hot gases through the flue and then through the 40 drum and means for feeding materials into the end of the drum which communicates with said fan, said feeding means projecting into the end of the arm and being arranged to obviate the necessity of materials 45 having to pass the fan intake before entering the drum.

FREDERICK T. GREAVES.
